UNITED STATES PATENT OFFICE.

FRANK L. HARDCASTLE, OF CHICAGO, ILLINOIS.

SHOE-RACK.

1,380,376.

Specification of Letters Patent. Patented June 7, 1921.

Application filed February 9, 1920. Serial No. 357,140.

To all whom it may concern:

Be it known that I, FRANK L. HARDCASTLE, a citizen of the United States, and a resident of the city of Chicago, county of Cook, and State of Illinois, have invented certain new and useful Improvements in Shoe-Racks, of which the following is a specification.

My invention relates to new and useful 10 improvements in shoe racks, and has for its object the provision of a shoe rack which will be simple in structure, economical in manufacture, and highly efficient in use.

Another object is the provision of a shoe 15 rack capable of accommodating a number of shoes.

Other objects will appear hereinafter.

The invention consists in the combinations 20 and arrangements of parts hereinafter described and claimed.

The invention will be best understood by reference to the accompanying drawings forming a part of this specification, and in which,

25 Figure 1, is a plan view of the invention, Fig. 2 is a sectional view taken on substantially line 2—2 of Fig. 1, and

Fig. 3, is a fragmentary sectional view 30 illustrating the retaining loops.

The preferred form of construction comprises a plate 6 which is made preferably of sheet metal and provided with an elongated slot 7, which is formed by punching out of the sheet 6 a lip 8. The lip 8 is serrated 35 along its free edge to provide teeth, the lip 8 being curled so that the teeth 9 project vertically when the plate 6 is fastened upon a wall or other suitable retaining member. As shown in Fig. 1, the slot 7 is interrupted 40 by a rib 10. By forming the device in this manner there are virtually two slots 7 with two corresponding lips 8. The rib 10 reinforces the plate 6 and gives greater rigidity to the device than would be the case if 45 it were not present. Adjacent the lower edge of the member 6 are formed a series of slots 10' which are spaced apart by intervening portions 11 of the member 6. A suitable strap or fabric member or other flexible 50 element is laced through the slots 10', as shown in Fig. 3, so as to provide loops 12 adapted to receive the toe of the shoe or slipper 13, the heel thereof being engaged by the teeth 9. When a shoe is placed upon 55 the rack in this manner, the same is firmly held thereon and misplacement of the shoes by the wearer rendered less liable. At each

end of the flexible element may be formed a suitable knot to retain the same in laced position and by forming this flexible element 60 from one single piece, the loops 12 may be adjusted to accommodate different shoes having various sized toes, so that the shoe irrespective of its size or shape may be placed upon the rack and firmly held. 65

While I have illustrated and described the preferred form of construction for carrying my invention into effect, this is capable of variation and modification without departing from the spirit of the invention. I, therefore, do not wish to be limited to the precise 70 details of the construction set forth, but desire to avail myself of such variations and modifications as come within the scope of the appended claims. 75

Having described my invention, what I claim as new and desire to secure by Letters Patent is:—

1. A device of the class described comprising a plate; a lip cut out and bent up from 80 said plate adapted to engage the heel of a shoe; and an adjustable loop-forming member adjacent one edge of said plate adapted to receive a toe of said shoe, substantially as described. 85

2. A device of the class described comprising a plate member at the edge of said slot, provided with an interrupted elongated slot; an interrupted serrated lip on said member; and adjustable loop-forming means on said 90 member, substantially as described.

3. A device of the class described comprising a plate member, having an elongated slot therein; a reinforcing rib interrupting said slot; interrupted lips integral with said 95 plate member and bent up from said slot; and adjustable loop-forming means laced in said plate adjacent one edge thereof, substantially as described.

4. A shoe rack comprising a plate; a serrated lip struck up from the upper portion of said plate, at the edge of an elongated slot, and adapted to engage the heels of shoes; and a flexible member laced through the lower portion of said plate, provided with 105 adjustable loops for receiving the toes of said shoes. 100

In testimony whereof I have signed my name to this specification in the presence of two subscribing witnesses.

FRANK L. HARDCASTLE.
